US00D528975S

(12) **United States Design Patent** (10) Patent No.: **US D528,975 S**
Chi et al. (45) Date of Patent: **** Sep. 26, 2006**

(54) **BATTERY FOR POWER TOOL**

(75) Inventors: **Wen-Yao Chi**, Taichung (TW);
Lien-Sheng Chuang, Taichung (TW)

(73) Assignee: **Mobiletron Electronics Co., Ltd.**,
Taichung Hsien (TW)

(**) Term: **14 Years**

(21) Appl. No.: **29/234,912**

(22) Filed: **Jul. 26, 2005**

(51) LOC (8) Cl. **13-02**

(52) U.S. Cl. **D13/103**

(58) Field of Classification Search D13/102-106,
D13/110, 118-119, 184; 429/96-100, 163,
429/176

See application file for complete search history.

(57) **CLAIM**

The ornamental design for a battery for power tool, as shown.

DESCRIPTION

FIG. 1 shows a perspective view of the present design.
FIG. 2 shows a right side elevational view of the present design.

FIG. 3 shows a top plan view of the present design.

FIG. 4 shows a front elevational view of the present design.

FIG. 5 shows a bottom plan view of the present design.

FIG. 6 shows a left side elevational view of the present design; and,

FIG. 7 shows a rear elevational view of the present design.
